UNITED STATES PATENT OFFICE.

OMAR H. JEWELL AND WILLIAM M. JEWELL, OF CHICAGO, ILLINOIS, ASSIGNEES TO THE O. H. JEWELL FILTER COMPANY, OF SAME PLACE.

STERILIZER.

SPECIFICATION forming part of Letters Patent No. 637,796, dated November 28, 1899.

Application filed March 26, 1897. Serial No. 629,295. (No model.)

To all whom it may concern:

Be it known that we, OMAR H. JEWELL and WILLIAM M. JEWELL, citizens of the United States, residing in Chicago, in the county of 5 Cook and State of Illinois, have invented certain new and useful Improvements in Sterilizers, whereof the following is a specification.

The object of our invention is to provide a new and improved sterilizing apparatus, and 10 particularly one which will be well adapted for use in sterilizing water for potable purposes.

To this end our invention consists in providing an apparatus comprising means for killing all germs and means for afterward removing such germs, together with such other impurities as may be contained in the water or other liquid to be sterilized.

More particularly stated, said invention 20 consists in providing a suitable receptacle adapted to contain the water to be sterilized, with means for heating the water therein contained to a sufficiently-high temperature to sterilize it, and with means for filtering the 25 water after heating to remove the impurities therein contained, and also in providing means for cleansing the receptacle when necessary.

Our invention also comprises the particular arrangements and combinations hereinafter 30 described, and specifically pointed out in the claims.

Referring to the drawings, Figure 1 is a vertical section of our improved apparatus. Fig. 2 is an elevation of the same on a reduced 35 scale. Fig. 3 is a horizontal section on line 3 3 of Fig. 1. Fig. 4 is a horizontal section on line 4 4 of Fig. 1. Fig. 5 is an enlarged detail, being a sectional view showing one of the valves.

As shown in the drawings, 6 indicates a 40 tank of sheet metal or other suitable material, said tank being closed and adapted to contain the liquid to be purified. The bottom 7 of the tank 6 is preferably made concave, as shown 45 in Fig. 1.

8 indicates a fire-pot the lower portion of which is surrounded by a water-jacket 9, as shown in Fig. 1.

10 indicates the door of the fire-pot.

50 11 indicates a peripheral flange formed at the upper portion of the fire-pot 8, which is

adapted to receive and support the tank 6. A channel is provided in the outer surface of said flange to prevent displacement of the tank, and, as shown, said channel is somewhat wider than the lower edge of the tank 55 in order to allow for expansion.

As shown in the drawings, the fire-pot 8 is preferably made in several sections for facilitating casting.

12 indicates the smoke-pipe of the fire-pot 8. As herein shown, the smoke-pipe 12 extends over said fire-pot up through the tank 6, and this construction is advantageous in that the smoke and heated gases passing up through 65 said smoke-pipe serve to heat the water in the tank, and therefore the construction shown is the most approved form of the invention. We do not wish to be limited, however, to the arrangement of the smoke-pipe as shown, as 70 in some cases said smoke-pipe may be otherwise arranged—as, for instance, where the means for heating the water in the tank are ample without utilizing the heat of the gases from the fire-pot.

13 indicates a filter-tank open at the top, which filter-tank is arranged in the tank 6 near the lower portion thereof, as shown in Fig. 1. The filter-tank 13 is adapted to contain a suitable bed of filtering material, such 80 as sand or crushed quartz.

14 indicates a hollow casting, which is arranged immediately below the filter-tank 13 and communicates therewith by means of strainers 15 of the type commonly used in filters. The strainers serve to prevent the sand or other filtering material from entering the casting 14. As best shown in Fig. 1, the inner portion of the casting 14 is beveled or inclined, for purposes which will be hereinafter 90 stated.

The casting 14 is supported upon legs 16 at one side and at its opposite side by means of a boss 17, which receives a screw-threaded pipe 18, extending through the wall of the 95 tank 6, as shown in Fig. 1. A lock-nut 19 serves to prevent loosening of said pipe.

The pipe 18 is connected to a pipe 20, arranged beside the apparatus, preferably in a vertical position, which pipe communicates 100 through a branch 21 with a water-supply. A valve 22 opposite the outer end of the pipe 18

- 5 serves to open or close communication between the pipe 18 and the pipe 20, as shown in Fig. 5. The valve 22 is preferably of the usual screw-plug type, as shown in Fig. 5.
- 5 23 indicates a second valve arranged in the pipe 20 below the valve 22. The valve 23 is for the purpose of shutting off communication between the upper and lower portions of the pipe 20.
- 10 24 indicates a pure-water outlet-pipe provided with a valve 25, said outlet-pipe communicating with the pipe 18, as shown in Fig. 2.
- 15 26 indicates a pipe which communicates with the pipe 20 below the valve 23 and with the tank 6 near the lower portion thereof, as shown in Fig. 1.
- 20 27 indicates a fresh-water coil which is arranged in the tank 6 at the upper portion thereof and communicates at one end with the upper end of the pipe 20 by means of a pipe 28.
- 25 29 indicates a valve for closing communication between the pipe 20 and the coil 27.
- 30 30 indicates a pipe which communicates with the upper end of the coil 27 and serves to conduct water therefrom.
- 35 31 indicates a steam-coil which is arranged in the tank 6 at the bottom thereof below the filter-tank, as shown in Fig. 1.
- 30 and 33 indicate inlet and outlet valves for said steam-coil.
- 34 indicates a central flue extending up through the filter-tank 13 and partially through the coil 27, as shown in Fig. 1. The flue 34 is preferably made in sections, as shown.
- 40 As illustrated in Fig. 1, the beveled portion of the casting 14 forms a funnel leading to the flue 34, thereby facilitating the flow of the currents of water up through said flue, as will be hereinafter described.
- 45 35 indicates a pipe which connects the lower end of the pipe 20 to the water-jacket 9, as shown in Fig. 1.
- 45 36 indicates a pipe which connects with the water-jacket 9 and with the tank 6, preferably on a level with the upper end of the flue 34, as best shown in Fig. 2.
- 50 37 indicates a pipe which communicates with the top of the tank 6 and also by a pipe 38 with the bottom thereof, as shown in Fig. 1.
- 39 indicates a valve similar to the valve 22, which serves to close the pipe 38.
- 40 40 indicates a hand-hole at the lower portion of the tank 6.
- 55 As already stated, our improved apparatus provides for heating the liquid to be sterilized and afterward filtering the same. The liquid to be sterilized is contained in the tank 6, being supplied thereto through pipes 21 20 26, the pipe 18 being closed by the valve 22 during the operation of filling said tank and the valve 23 being open. When the tank has been filled, the valves 23 29 are closed, the pipe 18 being allowed to remain closed. The 65 valve 25 in the pure-water outlet-pipe is also kept closed until the water in the tank has been heated sufficiently to sterilize it. The
- heating of the water is accomplished either by steam or by heat from the fire-box 8. When steam is used, it is passed through the coil 31 at the bottom of the tank 6. The water immediately surrounding said coil being thereby heated rises through the flue 34, the colder water near the outside of the tank descending, so that a regular circulation is obtained, until all the water in the tank is heated to the proper temperature. When heat from the fire-box 8 is used, the circulation of the water is substantially the same, and it is materially assisted by heat from the smoke-pipe 12, which causes the water immediately surrounding said pipe to flow upward. In this operation the beveled form of the casting 14 is a material benefit, as it facilitates the passage of the water to the flue 34. The arrangement of the filter-bed within the tank 6 is especially advantageous, for the reason that the filter-bed is thereby sterilized also by the heated water. After the water has been sufficiently sterilized by heat the valve 29 is opened, permitting cold water to flow through the coil 27 to cool the water in the tank, said water circulating continuously through the coil 27, being discharged through the pipe 30. The valve 25 in the pure-water pipe is then opened, permitting the water in the tank 6 to pass downward through the filter-bed and casting 14 to the pure-water outlet-pipe 24, whence it may be conducted to any suitable point. When the tank has been emptied, it may again be filled with impure water and the operation above described repeated as often as may be desired.
- As the impurities are removed from the water by the filter-bed such bed in time becomes foul and must be washed. For this purpose the pure-water valve 25 is closed and also the valve 23. The valve 22 is then opened, permitting water from the pipe 20 to pass into the casting 14 and thence up through the strainers 15 and filter-bed, overflowing the sides of the filter-tank and carrying the impurities from the filter-bed into the lower portion of the tank 6, whence they may be drawn off through pipes 38 37, the valve 39 being open for this purpose. After the bed has been washed sufficiently the pipe 18 is closed by means of the valve 22, and the valve 39 is closed to prevent the escape of water from the tank. The result is that water from the pipe 20 passes through the pipe 26 into the lower portion of the tank 6, and this may be continued until the tank is full. Heat is then applied and the operation of sterilizing above described repeated. The upper portion of the pipe 37 serves to carry off the overflow from the tank 6.
- When the fire-pot 8 is used for heating the water in the tank, such heating is further facilitated by the water-jacket 9, the water in which becomes heated and is conducted into the upper portion of the tank 6.
- We have described our invention in detail, but wish it to be understood that we do not

wish to be restricted to the specific details of the apparatus described, except where specifically claimed, as various modifications may be made without departing from our invention.

5 That which we claim as our invention, and desire to secure by Letters Patent, is—

1. In a sterilizing apparatus, the combination with a water-tank of a filter-tank arranged therein, means for admitting water to said water-tank, means for heating the water therein, an outlet from said filter-tank, a valve controlling said outlet, whereby the filtration of the water in said water-tank may be prevented, and means for reversing the flow of water through the filter-tank, substantially as described.

2. In a sterilizing apparatus, the combination with a water-tank of a filter-tank of less diameter, in the lower portion thereof, a cold-water coil in the upper portion of said water-tank, heating apparatus below said filter-tank, and a central water-passage extending from the lower to the upper portion of said water-tank through the filter-tank, whereby the water in said water-tank may be caused to circulate about said filter-tank, substantially as described.

3. In a sterilizing apparatus, the combination with a water-tank of a filter-tank of less diameter, in the lower portion thereof, a cold-water coil in the upper portion of said water-tank, heating apparatus below said filter-tank, a central water-passage extending from the lower to the upper portion of said water-tank through the filter-tank, and a flue communicating with the heating apparatus and

extending through said water-tank within said water-passage, substantially as described.

4. In a sterilizing apparatus, the combination with a tank 6, and a filter-tank 13 therein, of a pipe 20, pipe 18 connecting said pipe 20 to said filter-tank, pipe 26 connecting said pipe 20 with said tank 6, a pure-water pipe 24 connecting with said pipe 18, and valves 22 25 for the pipes 18 24 respectively, substantially as described.

5. In a sterilizing apparatus, the combination with a tank 6, and a filter-tank 13 therein, of a pipe 20, pipe 18 connecting said pipe 20 to said filter-tank, pipe 26 connecting said pipe 20 with said tank 6, a pure-water pipe 24 connecting with said pipe 18, valves 22 25 for the pipes 18 24 respectively, a cold-water coil within said tank 6, a pipe 28 connecting said coil with said pipe 20, and a valve 29 for said pipe 28, substantially as described.

6. In a sterilizing apparatus, the combination with a tank 6, and a filter-tank 13 therein, of a pipe 20, pipe 18 connecting said pipe 20 to said filter-tank, pipe 26 connecting said pipe 20 to said tank 6, a pure-water pipe 24 connecting with said pipe 18, valves 22 25 for the pipes 18 24 respectively, a cold-water coil within said tank 6, a pipe 28 connecting said coil with said pipe 20, a valve 29 for said pipe 28, an outlet-pipe 38, and a valve 39 therefor, substantially as described.
